UNITED STATES PATENT OFFICE

ALBERT V. PASLEY, OF RHEA, ARKANSAS

TOY AEROPLANE

Application filed May 22, 1931. Serial No. 539,351.

This invention relates to a toy aeroplane, the general object of the invention being to provide a casing on the end of a stick, with an aeroplane having foldable wings adapted to be placed in the casing, with a flexible member for connecting the plane with the stick, so that by removing the plane from the casing and stretching its wings and then attaching one end of the flexible member to the plane and the other to the stick, the plane can be made to fly by imparting a rotary motion to that end of the stick which is connected with the flexible member.

A further object of the invention is to provide simple means for holding the wings of the plane in stretched condition, while permitting the wing to be folded so that the plane can be placed in the casing.

This invention also consists in certain other features of construction and in the combination and arrangement of the several parts, to be hereinafter fully described, illustrated in the accompanying drawings and specifically pointed out in the appended claims.

In describing the invention in detail, reference will be made to the accompanying drawings, wherein like characters denote like or corresponding parts throughout the several views, and in which:

Figure 1 is a top plan view of the plane.
Figure 2 is a side view thereof.

Figure 3 is a bottom plan view.

Figure 4 is a front end view of the plane.

Figure 5 is a section on line 5—5 of Figure 1.

Figure 6 is a sectional view through the casing, showing the plane therein.

Figure 7 is a view showing how the device is used.

In these drawings, the letter A indicates a toy aeroplane which comprises the body 1 having a propeller 2 at its front end and the horizontal tail piece 3 at its rear end. A vertical rudder 4 is movably connected with the tail piece so that it can be moved from a horizontal position to a vertical position and vice versa, as shown in Figure 5, the rudder being moved to a horizontal position when the plane is placed in the casing B, which

is attached to the stick 5. The wing 6 of the plane is formed of foldable material and rods 7 are passed through casings formed at the front edges of the wing. These rods are pivotally connected with the body, as shown at 8. Bars 9 are pivotally connected with the rods 7. The rear ends of the bars 9 have eyes 10 formed thereon for slidably engaging the bars 11 suitably fastened to the body, one at each side thereof. Notches 12 are formed in the body for receiving portions of the eyes 10 when the parts have been moved to a position to hold the wing parts in unfolded position. By exerting a slight pressure on the bars 9, the eyes can be removed from the notches so that the bars can be moved rearwardly on the bars 11, which will swing the rods 7 against the sides of the body and this movement will cause the wing parts to fold on the lines 13, as shown in Figure 6. When the eyes engage the notches, the parts will be held with the wing in unfolded position. Thus it is simply necessary to remove the device from the casing and then move the parts to hold the wing in unfolded position and then move the rudder 4 into vertical position. After this is done, a string 14, attached to the plane, is attached to an eye 15 at the end of the stick so that by grasping the casing and whirling the stick, the plane will be caused to fly in a circle, as shown in Figure 7. When it is desired to no longer use the device, the wing parts are folded and the rudder 4 turned down and then the device is placed in the casing B, which is provided with a hinged cover 16. A bar 17 passes through the body of the plane and has an eye 18 at each end thereof for receiving one end of the string 14. By attaching the string to either end of the bar 17, the device can be used by a right hand person or a left hand one.

It is thought from the foregoing description that the advantages and novel features of the invention will be readily apparent. It is to be understood that changes may be made in the construction and in the combination and arrangement of the several parts, provided that such changes fall within the scope of the appended claims.

What I claim is:

1. A device of the class described comprising a toy consisting of a body, a wing formed of foldable material, bars connected with the front edge of the wing and pivotally connected at their inner ends with the body, a pair of bars pivotally connected with certain of the first mentioned bars, a rod at each side of the body and the second mentioned bars having eyes through which the rods pass, said body having notches therein for receiving portions of the eyes to hold the parts with the wing in unfolded position, a horizontal tail piece fastened to the rear end of the body and a rudder hingedly connected with the tail piece whereby the rudder can be moved from a horizontal to a vertical position and vice versa.
2. A device of the class described comprising a toy consisting of a body, a wing formed of foldable material, bars connected with the front edge of the wing and pivotally connected at their inner ends with the body, a pair of bars pivotally connected with certain of the first mentioned bars, a rod at each side of the body and the second mentioned bars having eyes through which the rods pass, said body having notches therein for receiving portions of the eyes to hold the parts with the wing in unfolded position, a horizontal tail piece fastened to the rear end of the body, a rudder hingedly connected with the tail piece whereby the rudder can be moved from a horizontal to a vertical position and vice versa, a rod passing through the body and having an eye at each end thereof and a flexible member adapted to be connected with either eye.

In testimony whereof I affix my signature.

40 ALBERT V. PASLEY.
